[57] CLAIM

The ornamental design for a combined pressure and
temperature gauge unit, as shown.

DESCRIPTION

FIG. 1 is a front elevation of the combined pressure and
temperature gauge unit embodying my new design;
FIG. 2 is a right side elevation of the meter of FIG. 1;
FIG. 3 is a rear elevation of the combination meter of
FIG. 1;
FIG. 4 is a bottom plan of the combination meter of
FIG. 1;
FIG. 5 is a fragmentary sectional view taken on line
5—5 of FIG. 4.
